INVENTOR

Robert B. Killgore
ATTORNEY

frame, an ink pad mechanism comprising an ink pad holder, a resilient strip on the holder, side bars to one end of which the holder is pivotally secured, the other ends of the side bars being pivotally secured to the hand stamp frame and a pair of links pivotally secured at one end to the middle portions of the side bars and also pivotally

secured to the printing mechanism, the ends of the side bars being flattened on the bottom to engage the ends of the resilient strip and angularly cut off at the rear, lower part to engage the resilient strip. ¹⁰

In testimony whereof I have affixed my signature.

CHARLES SPIELMAN.
